CLAIM

We claim the ornamental design for a protective case for mobile communications device, as shown and described.

DESCRIPTION

FIG. 1 is a front, right-side, and top perspective view of a protective case for mobile communications device, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, right-side, and top perspective view thereof showing an environmental device within the case.

The broken lines throughout the drawing figures depict portions of the protective case for mobile communications device and an environmental device that form no part of the claimed design.
